**MEANS FOR EXPELLING AIR FROM FOLDED
NEWSPAPERS IN A PRESS-CONVEYOR DELIV-
ERY SYSTEM**

Frank A. Smethurst, Salt Lake City, Utah, assignor to Kearns Tribune Corporation, Salt Lake City, Utah, a corporation of Utah, and Deseret News Publishing Company, Salt Lake City, Utah, a corporation of Utah, jointly

Filed Oct. 2, 1963, Ser. No. 313,358
10 Claims. (Cl. 271—76)

The present invention relates to newspaper press and conveyer delivery systems and, more particularly, to an improvement therein wherein suitable means are provided for expelling the air from folded newspapers at a remote point in the delivery system such that chances of ink smearing are avoided and stacking and further transport of the newspapers are aided.

In the past a number of different types of newspaper press and conveyer delivery systems have been developed. Generally common to these is conventional single or multiple press unit supplied with a heavy duty newspaper conveyer system which conducts a newspaper run upwardly from the press proper to an extended overhead conveyer system of the overall newspaper conveyer. The overhead leg of the newspaper conveyer is generally quite long. This is for two reasons. In the first place, plant engineering principles generally indicate that final delivery points, stacking tables, and binding equipment are best disposed remote from the actual press equipment and near the loading docks of the plant, where the bundles are delivered to trucks and other vehicles for distribution. In the second place, and most important, is a desire that there be a relatively long overhead run of the newspapers in order to allow sufficient time for the newspapers to dry prior to their stacking at a remote point. For this purpose the presses and their built-in folding equipment are adjusted so that a relatively loose fold of the individual papers is made immediately prior to the delivery of the newspapers to the conveyer system. Such loose folding avoids smearing and double printing and, additionally, permits air to be retained in the paper to aid in the drying process of the printing.

Heretofore, the binders have been relied upon to squeeze the air out of the newspapers at the time when the papers are bound into bundles by rope, wire, metal straps, or other means. However, the expelling of air from a stack of newspapers is less effective than if the newspapers are individually compressed, in the course of their run, to accomplish such expelling of air. Furthermore, in order for the newspapers to be delivered properly to the binders it is important that they be stacked and conveyed to the binders. Personnel in newspaper plants readily attest to the fact that stacks of newspapers as are made up from the conveyer output of a newspaper run in a conventional press and conveyer are often very unwieldy, and the stacks tend to become disarrayed during transit to the binders, particularly where changes of a direction are encountered in the travel path to the binders. It would be a great advantage if the air were automatically expelled from the newspapers after sufficient time has elapsed in order for newspapers from a run to dry and immediately prior to stacking the papers so that the stacks formed thereby will not lose their erectness as they proceed along subsequent conveyer means to the binding equipment.

Accordingly, a principal object of the present invention is to provide an improvement in newspaper press con-

2

veyer systems wherein appropriate means is provided near the delivery end of the conveyer system for squeezing air out of the newspaper run as it proceeds toward the stacking area.

5 A further object of the present invention is to provide means for automatically expelling air from a newspaper run at an advantageous point remote from the press proper of a press, newspaper conveyer system.

A further object of the invention is to provide tension roller means adapted to bear upon the idler roller or power roller, or endless belting thereof, of a leg of the conveyor system remote from a newspaper press, this in order to expell air from the newspaper run and permit the same to be advantageously stacked for further transport and binding.

15 A further object of the invention is to provide adjustable tension means which is easily manipulated by hand for regulating the amount of pressure imposed upon a newspaper run in order to expell the air from the newspapers and to sharpen the leading or fold edges of the 20 individual newspapers so that they can be stacked in the most appropriate manner.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings in which:

30 with the accompanying drawings in which:
30 FIGURE 1 is a side elevation, partially in schematic
form, of a conventional press and conveyer construction
wherein the same employs the subject of the present in-
vention, namely, a suitable tension roller designed to
35 exhaust air from the individual papers of a newspaper
run at an advantageous point along the conveyer line of
travel; in FIGURE 1 the structure shown with respect to
the heavy conveyer is somewhat simplified in form, with
40 the side plate thereof removed for clarity, the gearing,
chain drive, and ancillary equipment likewise, to show
simply the placement of idler and drive rollers, their
belting and the output delivery system of the conveyer.

FIGURE 2 is an enlarged fragmentary view, taken along the line 2—2 in FIGURE 1, illustrating that portion of the conveyer structure which accommodates the tension roller structure and adjustment means which is the subject of the present invention.

FIGURE 3 is a side elevation, principally in schematic form and taken along the line 3-3 in FIGURE 2, of the final turn in the delivery system of the conveyer structure prior to the newspaper run reaching a retaining area and 50 a terminal or near terminal conveyer belt.

In FIGURE 1 constant delivery press 10 is shown in block diagram form and is strictly conventional. A popular press of this type currently used is the Goss press, as the same is known to the trade.

55 Heavy-duty newspaper conveyer 11 is likewise conventional and may take any standard form such as that currently manufactured by the Cutler Hammer Company and designated a model 70, heavy-duty newspaper conveyer with electronic drive.

The upward-travel, initial leg 1 of the conveyer is disposed at 12 so as to receive pre-folded newspapers from press 10 in a conventional manner. For convenience of illustration the major part of the conveyer is indicated merely in dotted lines. The elongate overhead leg O of the conveyer 11 will be quite long; hence, for convenience of illustration the overall conveyer 11 is shown broken at its dotted line configuration at 13. The descending-travel, final leg 14 of the newspaper conveyer

is shown somewhat in detail, but with conventional drive chains and sprockets and similar hardware not being shown, this for convenience of illustration.

Of importance is the fact that the newspaper conveyer 11 will include a multiplicity of endless conveyor belts 15, 16, and 17, 18, and 19, 20, and so on, in order that the newspapers conveyed from press 12 may be carried by adjacent, slightly spaced, corresponding belting (i.e. 15, 16 and 17, 18 and 19, 20) from the press 10 to a final area 21 which is defined by the conveyer and suitable resilient retainer fingers 22, one of which is illustrated. A suitable number of pulleys and rollers will be supplied the newspaper conveyer in a conventional manner in order that the paper run might turn corners as at A in FIGURE 1 so as to descend along the final leg 14 of the conveyer to area 21. There will be at least one drive (or driven) roller (e.g. 23) for each run of endless belting. All of the drive rollers are conventionally ganged together by suitable chain means (not shown) in order that the rotational movement of the drive rollers move with the same speed. Idler rollers 24 are supplied along opposite sides of the newspaper run between endless belting 15-16, 17-18, and so forth, in order to support the belting to accommodate a straight run of papers.

As the newspapers emerge from controlled delivery area 21 they are placed on a final conveyer belt 25 running on delivery rollers 26 and 27, at least one of which is driven, so that the newspapers arrive at bed 28 for further routing. Generally, men will be disposed at bed 28 to stack the papers in groups of 10's or 20's, for example, and place the stacked newspapers on another conveyer for bundling preparatory to loading trucks with the newspapers.

The structure thus far described is strictly conventional.

As before indicated, the difficulty of stacking the papers at or near bed 28, in a manner such that the stacks will not fall over or otherwise become disorganized in their routing to bundling apparatus or to further conveyer structure, is solved by the incorporation in the conveyer structure above described of suitable tension roller means which is now to be explained. Again, the tension roller means is provided to sharpen the folded, leading edge of the newspapers as they come down the conveyer and, in addition, press out of the newspapers practically all of the air that would otherwise keep the individual newspapers quite bulky and unsuited for stacking and transport purposes.

The invention consists in the supplying of a tension roller 30 which, as shown in FIGURE 2, is appropriately journaled upon fixed shaft 31 by bearing means 32. Opposite extremities 33 and 34 of shaft 31 are received in and hence mounted to receptacles 35 and 36, these latter forming integral parts of arms 37 and 38. The arms are journaled by pivot bolts 39 and 40 and by means of bolt-receiving means 41 and 42, the latter being secured to the conveyer frame 43.

The arms 37 and 38, accordingly, are freely swingable about the axes of pivot bolts 39 and 40, and the shaft 31 coupled thereby, by means of receptacles 35 and 36, is adapted for adjustment in slight, arcuate movements, and will conform to contour of the paper run passing between conveyer belts 17 and 18, for example.

Affixed to arms 37 and 38 at receptacles 35 and 36, for example, are tension springs 40 and 41, the remaining extremities of which are suitably mounted to adjustment straps 42 and 43. These adjustment straps are of metal, are provided with a plurality of longitudinally and mutually aligned apertures 44 and are also provided with respective handles 45 and 46. Mounted to the press frame proper are inwardly turned fingers 47 and 48 which are dimensioned to be received by any one of the several apertures 44 of the individual adjustment straps 42 and 43. Accordingly, the degree of force exerted by tension roller 30 or the endless belting which it carries and that side of the newspaper run which is opposite to a particular idler roller (see FIGURE 1) may be adjusted by

operator urging the handles 45 and 46 inwardly in the direction of the arrows shown so that inwardly-turned fingers 47 and 48 may engage different respective apertures 44 which are closer to or farther from the junctures 5 of the adjustment straps 42 and 43 with their respective tension springs 40 and 41.

Now it may be that the rollers will be so designed that the belting thereof protrudes slightly outwardly away from the outer periphery of the rollers proper. This being the case, the above principle will still apply since the pressure upon the newspaper run, so as to squeeze as much air as possible out of the individual papers, may be controlled by the selected positioning of adjustment straps 42 and 43, this through the employment of handles 45 and 46 for convenience of the operator.

FIGURES 1 and 3 illustrate the path of general newspaper travel, see arrows 46 in FIGURE 3. By way of further explanation, the endless belts are advantageously wire belting configured in the form of tightly wound tension springs (see 18, for example, FIGURE 2). This is strictly conventional in the art. Also conventional is the fact that the several rollers such as rollers 24 and 24' in FIGURE 2 are appropriately grooved to receive the several endless wire belts 18, for example. FIGURE 3 indicates the manner in which the handles 45 are moved so as to accomplish a tightening or loosening adjustment upon tension roller 30, as desired.

The press 10 when operating performs the complete printing, cutting and folding operation to produce a series 30 of newspapers stepped somewhat in the pattern as indicated at N in FIGURE 1. These newspapers are conveyed in a conventional manner by the conventional conveyer 11 along an upward leg I, an extended horizontal leg O, and finally down the vertical leg 14, passing all 35 while between adjacent conveyer belt series, for examples, 17, 18, until the papers pass underneath a lowermost roller 24 to be ejected outwardly in the direction of the arrows in FIGURE 3 so as to be disposed in area 21 underneath resilient retainer fingers 22. These retainer fingers, which are conventional, regulate the outward flow of the newspapers so as to allow them to adjust gradually to the new and horizontal orientation of the papers along final conveyer belt 25.

During the passage of the newspapers between adjacent 45 series of endless conveyer belts 17, 18, the papers will traverse an area backed by idler roller 24'. Disposed on the opposite side of the newspaper run at this point is tension roller 30 which with its conveyer belt is urged toward idler (or drive) roller 24' and hence along the 50 opposite side of the newspaper run so as to compress the papers at this point, the degree of compression and pressure being adjustable by virtue of the provision of adjustment straps 42, 43. Again, the tension roller 30 is adapted to swing in and out slight incremental displacements about the axes of the aligned stub-pivot axles or 55 bolts 39 and 40. For "thin" newspapers, takeup will be made by releasing the adjustment straps 42 and 43 from their respective fingers 47 and 48 and then urging the corresponding handles 45 and 46 outwardly so that the fingers may engage new adjustment strap apertures 44. 60 For heavier issues apertures 44 near the respective handles 45 and 46 will be selected for engagement with the two inwardly turned fingers 47 and 48.

FIGURE 1 illustrates the situation where a belt B may 65 be used to couple, by means of pulleys P and P', power from the drive roller 23 to tension roller 30. This will be a desired condition to maintain where an especially heavy paper run, i.e., thick newspapers, is to be made. For most purposes, however, tension roller 30 can simply be an idler roller and uncoupled with respect to any drive source 70 as indicated in FIGURE 3.

It has been noted in the above discussion and in the drawings that, preferably, the tensioning means for the tension roller of the present invention be disposed on both sides of the roller and the handles 45 and 46 adjusted

simultaneously. While this is desired, to reduce bearing and journal wear as much as possible, yet it would be quite possible to actuate a tension roller from one side only.

All of the rollers, both drive and driven rollers, idler rollers and the tension roller of the present invention, may comprise single rollers or split coaxial rollers, as desired.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. In a newspaper press, conveyer system comprising press means for delivering a constant output of overlapping newspapers, and conveyer means for transporting said newspapers to a remote point, said conveyer means including a frame and comprising a newspaper-run, upward-travel initial leg, an elongate, cross-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; an improvement comprising tension roller means disposed proximate and parallel to a cooperating one of said rollers of one of said legs and on the opposite side of one of said paths and remote from said press, means for journalling said tension roller means to said frame about an incrementally displaceable axis parallel to said one roller, and means for springingly urging said tension roller means in a transverse direction toward said belting and said one roller to compress nominally said travel path and such newspapers as progress therein, wherein said journalling means comprises a pair of vertical, swingable, pivot arms journaled at their upper extremities to said frame and a horizontal shaft coupled to said arms at their lower extremities, spanning the same, said tension roller being revolvably disposed upon said shaft, and wherein said springingly urging means comprises tension spring means coupled to said shaft, adjustment strap means connected to said tension spring means, handle means affixed to said adjustment strap means, said adjustment strap means including plural adjustment apertures, said frame being provided with transverse finger means dimensioned for reception by a selected one of said apertures, said finger means being so engaged by said adjustment strap means.

2. In a newspaper press, conveyer system comprising press means for delivering a constant output of overlapping newspapers, and conveyer means for transporting said newspapers to a remote point, said conveyer means including a frame and comprising a newspaper-run, upward-travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; an improvement comprising tension roller means disposed proximate and parallel to a cooperating one of said rollers of one of said legs and on the opposite side of one of said paths and remote from said

press, means for journalling said tension roller means to said frame about an incrementally displaceable axis parallel to said one roller, and means for springingly urging said tension roller means in a transverse direction toward said belting and said one roller to compress nominally said travel path and such newspapers as progress therein, wherein said journalling means comprises a pair of vertical, swingable, pivot arms journaled at their upper extremities to said frame and a horizontal shaft coupled to said arms at their lower extremities, spanning the same, said tension roller being revolvably disposed upon said shaft, and wherein said springingly urging means comprises a pair of parallel, spaced tension spring means coupled at respective first extremities to said shaft, a pair of adjustment strap means respectively connected to said spring means at the remaining extremities, a pair of handle means respectively affixed to said strap means, each of said adjustment strap means including plural adjustment apertures, said frame being provided with selectively engageable, transverse finger means dimensioned for reception by a selected one of said apertures, said adjustment strap means being selectively engageable by said finger means for retention thereby.

3. In a newspaper press, conveyer system comprising press means for delivering a constant output of overlapping newspapers, and conveyer means for transporting said newspapers to a remote point, said conveyer means including a frame and comprising a newspaper-run, upward travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; an improvement comprising tension roller means disposed proximate and parallel to a cooperating one of said rollers of one of said legs and on the opposite side of one of said paths and remote from said press, means for journalling said tension roller means to said frame about an incrementally displaceable axis parallel to said one roller, means for springingly urging said tension roller means in a transverse direction toward said belting and said one roller to compress nominally said travel path and such newspapers as progress therein, and means for driving said tension roller means in the direction of newspaper conveyance.

4. A newspaper press, conveyer system comprising press means for delivering a constant output of overlapping newspapers, and conveyer means for transporting said newspapers to a remote point, said conveyer means including a frame and comprising a newspaper-run, upward-travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; and in combination with said newspaper press, conveyer system, an improvement comprising tension roller means disposed proximate and parallel to a cooperating one of said rollers of one of said legs and on the opposite side of one of said paths and remote from said press, means for journalling said tension roller means to said frame about an incrementally displaceable axis parallel to said one roller, and means for springingly urging said tension roller means in a transverse direction toward said

belting and said one roller to compress nominally said travel path and such newspapers as progress therein.

5. Structure according to claim 4 wherein said journaling means comprises a pair of vertical, swingable, pivot arms journaled at their upper extremities to said frame and a horizontal shaft coupled to said arms at their lower extremities, spanning the same, said tension roller being revolvably disposed upon said shaft.

6. Structure according to claim 4 wherein said springingly urging means comprises spring means for urging said tension roller means toward said cooperating one roller, means engaging said spring means at said spring means' extremity remote from said tension roller means, and means for adjusting the disposition of said engaging means relative to said frame and said cooperating one roller.

7. A newspaper press, conveyer system comprising press means for delivering a constant output of overlapping newspapers, and conveyer means for transporting said newspapers to a remote point, said conveyer means including a frame and comprising a newspaper-run, upward-travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; and in combination with said newspaper press, conveyer system, an improvement comprising tension roller means disposed proximate and parallel to a cooperating one of said rollers of one of said legs and on the opposite side of one of said paths and remote from said press, means for journaling said tension roller means to said frame about an incrementally displaceable axis parallel to said one roller, and means for springingly urging said tension roller means in a transverse direction toward said belting and said one roller to compress nominally said travel path and such newspapers as progress therein, wherein said journaling means comprises a pair of vertical, swingable, pivot arms journaled at their upper extremities to said frame and a horizontal shaft coupled to said arms at their lower extremities, spanning the same, said tension roller being revolvably disposed upon said shaft, and wherein said springingly urging means comprises tension spring means coupled to said shaft, adjustment strap means connected to said tension spring means, handle means affixed to said adjustment strap means, said adjustment strap means including plural adjustment apertures, said frame being provided with transverse finger means dimensioned for reception by a selected one of said apertures, said finger means being so engaged by said adjustment strap means.

8. A newspaper press, conveyer system comprising press means for delivering a constant output of overlapping newspapers, and conveyer means for transporting said newspapers to a remote point, said conveyer means including a frame and comprising a newspaper-run, upward-travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; and in combination with said newspaper press, conveyer system, an improvement comprising tension roller means disposed proximate and parallel to a coop-

ing one of said rollers of one of said legs and on the opposite side of one of said paths and remote from said press, means for journaling said tension roller means to said frame about an incrementally displaceable axis parallel to said one roller, and means for springingly urging said tension roller means in a transverse direction toward said belting and said one roller to compress nominally said travel path and such newspapers as progress therein, wherein said journaling means comprises a pair of vertical, swingable, pivot arms journaled at their upper extremities to said frame and a horizontal shaft coupled to said arms at their lower extremities, spanning the same, said tension roller being revolvably disposed upon said shaft, and wherein said springingly urging means comprises a pair of parallel, spaced tension spring means coupled at respective first extremities to said shaft, a pair of adjustment strap means respectively connected to said spring means at the remaining extremities, a pair of handle means respectively affixed to said strap means, each of said adjustment strap means including plural adjustment apertures, said frame being provided with selectively engageable, transverse finger means dimensioned for reception by a selected one of said apertures, said adjustment strap means being selectively engageable by said finger means for retention thereby.

9. A newspaper press, conveyer system comprising press means for delivering a constant output of overlapping newspapers, and conveyer means for transporting said newspapers to a remote point, said conveyer means including a frame and comprising a newspaper-run, upward-travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; and in combination with said newspaper press, conveyer system, an improvement comprising tension roller means disposed proximate and parallel to one of said rollers of said descending-travel, final leg and remote from said press, means for journaling said tension roller means to said frame about an incrementally displaceable axis parallel to said one roller, and means for springingly urging said tension roller means in a transverse direction toward said belting and said one roller to compress nominally said travel path and such newspapers as progress therein.

10. A newspaper press, conveyer system comprising press means for delivering a constant output of overlapping newspapers, and conveyer means for transporting said newspapers to a remote point, said conveyer means including a frame and comprising a newspaper-run, upward travel initial leg, an elongate, across-travel overhead leg communicating with said initial leg, a descending-travel, final leg communicating with said overhead leg, and a controlled delivery area contiguous with said descending-travel, final leg, each of said legs including respective sets of proximate, newspaper-transport-aiding endless belting and respective sets of rollers engaging said endless belting, said endless belting and said rollers of respective ones of said legs being so constructed and arranged as to define a newspaper travel path between adjacent endless belting, the travel paths of each of said legs being continuous; and in combination with said newspaper press conveyer system, an improvement comprising tension roller means disposed proximate and parallel to a cooperating one of said rollers of one of said legs and on the opposite side of one of said paths and remote from said press, means for journaling said tension roller means to said frame about an incrementally displaceable axis parallel to said one roller, means for springingly urging said tension roller means in a transverse direction toward

said belting and said one roller to compress nominally said travel path and such newspapers as progress therein, and means for driving said tension roller means in the direction of newspaper conveyance.
